UNITED STATES PATENT OFFICE

AUGUSTE WINKLER, OF BORDEAUX, FRANCE

SMOKELESS HEAT-ECONOMIZING APPARATUS FOR FURNACES OF ALL KINDS

Application filed March 12, 1925, Serial No. 15,088, and in France August 26, 1924.

This invention relates to furnaces and has for its object a smokeless heat economizing device, the purpose of which is to suppress the smoke in boilers with fixed movable or mechanical grates, ovens, retorts and, generally, in all apparatus utilizing solid, liquid or gaseous fuels; it presents, besides, the advantage of increasing the thermal efficiency by improving the utilization of the fuels.

10 The apparatus which is the object of the present invention is essentially constituted by one or several rows of injector nozzles designed to be housed in recesses made in one or several walls of the combustion chamber above the grate, at the back of same in the apparatus (boilers, etc.) and even in the flues, said arrangement having for its object to allow of placing the apparatus at highly heated places, near the fuel or the gases and to cause 15 the admission of the gases apt to support combustion at the very points where the combustion of the particles of free carbon or of the unburnt hydrocarbureted gases is to take place.

20 25 The apparatus provides also for the admission of the mixture apt to support combustion in proper conditions of quantity, composition, homogeneity, pressure and speed, according to the kind of fuel and the operation of the furnace.

The apparatus is essentially constituted by a passage disposed longitudinally on one or more walls of the combustion chamber and in which takes place the intimate mixture of air and steam which is subsequently injected therein and uniformly distributed in this chamber. The said passage is preferably constituted by elements placed side by side and provided with lateral orifices or vents for the issue of the gaseous mixture sent in the combustion chamber.

The appended drawing shows, as an example, a mode of realization of the smokeless heat economizer, the object of the invention.

Fig. 1 of this drawing is a view in elevation of a tubular element of the apparatus.

Fig. 2 is a horizontal section along 2—2.

Fig. 3 is a partial plan of an apparatus specially designed for going round the combus-

tion chamber the sides and the furnace bridge wall.

Fig. 4 is a transverse section along 4—4 of Fig. 1 and seen in the direction of the arrow.

As is seen on this drawing, the apparatus in which the air is drawn by the steam comprises in front a tuyère 1 which can be of any suitable type. This tuyère is disposed at the centre of a closing plate 2, of circular or conical form, and opens in a mixer 3 placed in front of a passage formed of elements 4 placed side by side, for example in cast iron or refractory material. The opening 4^a of said elements which is circular for example, as shown in Fig. 4, is provided laterally with a plane 4^b inclined from front to back on which opens the vents 4^c, of semi-conical or semi-cylindrical shape, disposed in regular rows or quincunx fashion, the axis of these vents may be inclined according to plane E—F to ensure thorough mixing of the combustion gases. The diameter of these vents varies according to the position of the row of nozzles with respect to the frontage or at the back of the combustion chamber. The diameter of the central opening 4^a can also be caused to decrease from the front (side at which the fuel is put in) to the back. Metallic diaphragms 5, with decreasing openings 5^a, are disposed from place to place between the elements 4. A casting 6 placed at the end of the passage closes the end of the passage, the elements constituting which are united by stays 7 passing in lateral openings 4^d permitting the easy removal of any one of the parts by the loosening of the extreme nuts. The whole apparatus may be introduced in a passage 8 constituted by U-shaped tiles of metal or refractory material housed in the brickwork.

The apparatus so constituted is placed along the walls of the furnace or oven, at a certain height above the grate (which height will vary according to the nature of the fuel used), either flush to the vertical wall or slightly in recess. In the case of combustion chambers of large capacity, several apparatus can be superposed on each wall.

In the construction shown in Fig. 4, the front face 4^e of the elements, which is exposed to the fire, has been set back a little

in the recess from the face of the brickwork: in this last case packing blocks of refractory materials disposed on either side of the apertures for the issue of the gaseous mixture can be advantageously housed in the groove so formed. A void can also be provided, if necessary, between the metal and the brickwork for causing a cooling stream of gas to circulate therein (for instance as in the case of the 10 interior furnace of a cylindrical boiler).

The working of the apparatus is as follows:

The steam arrives by the tuyère 1 and its quantity is regulated by a valve (not shown); 15 this steam carries with it by aspiration a variable quantity of air which can be adjusted by the operation of this valve and of the register 2, so that the quantities of air and steam are in proportion to the quality 20 of the fuel and to the manner in which the combustion proceeds. The intimate mixture of air and steam, obtained in the passage, is sent with maximum velocity, thanks to the dimensions of the tuyère in the tube 4, the 25 expansion of the steam being utilized with the maximum efficiency for carrying the air, as well as for the cooling of the metal. The action of the mixture of air and of vapour, distributed in the combustion chamber, completes the combustion resulting from the 30 action of the furnace grate or of the burners, according as the apparatus utilizes solid, liquid or gaseous fuels, by the introduction of gases apt to support combustion in the 35 mass of the non-burned hydrocarbureted gases. The air may be at ambient temperature or heated by the lost heat from the flues, the furnace, etc.

In this manner, the combustion of the particles of free carbon or of the hydrocarbureted gases is secured, in a portion or in the whole of the combustion chamber, hence the unused combustible is burned and consequently the efficiency of the furnace is improved.

The intimate mixture of air and of the steam and the adjustment of the outlet pressure of this mixture may be obtained by means of the perforated diaphragms 5 in the 50 case of the arrangement shown. This is obtained naturally in the case where the elements of the row have central apertures which decrease to form a tapering passage.

The elements of the passage could also be 55 of refractory material fitting one to the other and supported, for example, at the back, by the furnace bridge, and in front, by the front of the utilization apparatus. This arrangement is particularly adapted to the case 60 where combustion chambers with metallic walls like those of locomotives, boilers with internal furnace, etc., are used. The passages would be placed either at the lower portion or at the upper portion of the combustion chambers, as necessary.

It will be understood that the drawing in 70 of the air constituting the means apt to support combustion could be effected without the use of steam, by means of a fan or of a compressor discharging air in the passages. Gases apt to support combustion (oxygen, etc.) might be used instead of air or mixed with the air.

Having now described and ascertained the 75 nature of my invention, I declare that what I claim is:

A smokeless heat economizer, comprising a mixing box, means for admitting air and steam to said box, a conduit connected to said mixing box, said conduit being formed of a plurality of hollow rectangular elements having parallel external abutting faces and lateral downwardly inclined orifices for the injection of the mixture from the interior of the elements, tie rods for maintaining said elements assembled, lateral slots on each element through which said rods pass, whereby each element may be independently removed when the tie rods are loosened, and means to insure a constant pressure of mixture at 90 the orifices throughout the length of the conduit.

In testimony that I claim the foregoing as my invention I have signed my name.

AUGUSTE WINKLER.
